IGNITION SYSTEM AND APPARATUS

James A. Doran, Providence, R. I.

Application September 10, 1932, Serial No. 632,483
Renewed December 3, 1937

5 Claims. (Cl. 123—148)

This invention relates to ignition systems, and particularly pertains to ignition systems used for internal combustion engines.

The conventional battery ignition systems have many inherent disadvantages, due primarily to the construction and operation of their breaker contact points, ignition coils and spark plugs. Ordinary contact points usually have only a very small part of their surface in electrical contact, so that they burn and pit at one small point, and thus set up a serious resistance against the passage of current, particularly at starting speeds and at high speeds. When stronger coils are employed to compensate for the losses at the breaker points, the contacts burn proportionately faster. The conventional ignition coils also have several disadvantages which weaken their power and shorten their life.

To overcome these troublesome defects in ignition systems, I provide an ignition system with such improvements in the construction and operation of the component parts, as will produce the maximum spark strength required, with minimum current consumption, with lessened resistance at the breaker contacts, with elimination of burning and pitting of the contacts, with greatly increased durability and life of coil, and with generally improved results in the operation and power output of the engine. To accomplish these improvements I have devised and arranged the various elements of my ignition system with many novel features.

Thus, I have utilized what I term a transmuter in the system, to provide a periodic reversal of current through the breaker contacts. Preferably, I use a lever oscillating at half the speed of the breaker arm to make a contact on one side while the breaker arm is open, and to make a contact on the other side when the breaker arm next opens. The current supply is connected to two plates on the oscillating lever, one positive and the other negative; one pair of the receiving contacts is connected to the breaker arm and the other pair to the breaker screw, so that the breaker contacts have their polarity reversed at every opening. The reversal of current through the breaker contacts has important advantages, as hereinafter described.

With the above and other objects and advantageous features in view, the invention consists of a novel method of operation and assembly and a novel arrangement of parts more fully disclosed in the detailed description following, in conjunction with the accompanying

drawings, and more particularly defined in the claims appended hereto.

In the drawings,

Fig. 1 is a diagrammatical view showing the general plan of the ignition circuit; 5

Fig. 2 is a view similar to Fig. 1 showing a modified arrangement;

Fig. 3 is a vertical section through the distributor head on the line 3—3 of Fig. 4;

Fig. 4 is a plan view of the distributor head 10 with the cap removed;

Fig. 5 is a perspective view of the transmuter arm;

Fig. 6 is a perspective view of the rear plate 15 therefor;

Fig. 7 is a perspective view of the negative plate therefor;

Fig. 8 is a perspective view of one of the fixed contact frames;

Fig. 9 is a perspective view of the distributor 20 operating shaft showing the breaker and transmuter cams.

Referring to the drawings, the general circuit employed in my novel ignition system is diagrammatically shown in Fig. 1, and includes a line 25 circuit 10 for supplying current to the primary of the ignition winding 11, this circuit having a battery 12 and the usual switch 13. A condenser 14 is connected across the line, and a transmuter 15 is arranged to periodically reverse 30 the current supplied to a contact breaker 16 by alternately connecting points A to D and B to C, whereby the primary winding receives a periodically reversed current, instead of the usual direct current. The secondary winding is successively 35 connected, through the distributor arm 17, with contacts 18 for conducting the high tension current to the spark plugs 19 and 19', which are in series relation in the secondary circuit. Fig. 2 shows an alternative circuit that reverses through 40 the breaker points only, the parts being similarly designated; this type of circuit may be preferable when the coil is located at a distance.

It has been determined that the usual interrupted direct current carries particles of metal 45 from the negative contact face to the positive contact face of the breaker points, eventually eating holes in the negative contact point and building up, in irregular formation, the positive contact point. This transfer of metal occurs 50 when the contacts are arcing while being opened; as a result, the contact surfaces become so irregular and carbonized that the contact is poor and the high resistance restricts current flow. With such reduced current, the spark is weak- 55

ened and a high speed, high compression engine misses.

Clean contacts of large surface deliver the maximum current and operate an engine at much higher speed without skipping. At high speeds, the duration of contact is such an infinitesimal period of time that it is exceedingly important to provide the best possible contact surfaces. Furthermore, the breaking of corroded contacts is not sufficiently decisive to produce the desired powerful hot spark at each spark plug.

When the current at the breaker point is transmuted, and the polarity of the breaker contacts thus periodically reversed, there is no transfer of metal from one contact to the other, and there is no pitting or building up. Preferably, the current is reversed at every opening of the breaker contacts, although the transmuting mechanism may if desired be arranged so as to reverse less frequently, and may allow the breaker contacts to make several continuous openings with each polarity between each reversal of current. To avoid arcing at the transmuter switch, I design the actuating cams to open the breaker contacts while the transmuter switch is closed, and to reverse the transmuter switch while the breaker contacts remain open.

The transmuting mechanism may be mounted in any convenient location, but I prefer to mount the mechanism in the distributor as shown in Fig. 3 in order to simplify the construction and the wiring connections. The distributor has the usual body 20 and cap 21, the breaker and transmuter mechanism being mounted on the plate 22 which is preferably made of an insulation material such as fibre or Bakelite. The distributor shaft 23 extends vertically through the body and plate, and has the usual wiper 24 for distributing the high tension current to the terminal inserts 25 through the spring 26 from the central terminal insert 27, which receives high tension current from the coil. Mounted on the shaft 23 are the breaker arm cam 28 and the transmuter cam 29; the breaker cam, as shown in Fig. 5, having lobes 30 corresponding in number to the engine cylinders, and the transmuter cam having lobes 31 numbering half the breaker cam lobes.

Referring now to Fig. 4, the breaker arm 32 is shown formed of a fibre block 33 having a bumper projection 34 and a fulcrum bore 35 equipped with a metal, preferably brass, bushing 36 for mounting on the pivot pin 37 fastened to the distributor plate. A spring 38, preferably formed of a non-ferrous alloy of a high copper content, is riveted to the fibre block and its outer end under tension against a fixed post 38a. An extension 39 is also riveted to block 33, its outer end being provided with a contact 40 adapted to strike against the adjustable self-aligning contact 41 mounted on the distributor plate. As shown, the bumper 34 is pressed against the lobes 30, thus causing the breaker arm to oscillate on movement of the breaker cam, and allow the contact 40 to strike contact 41, closing and opening the circuit.

The transmuter mechanism includes a fibre bar 42 having a bumper projection 43 and a fulcrum bore 44 equipped with a metal bushing 45 for pivoted mounting on the pivot pin 46 fastened to the distributor plate. On the side of bar 42 is mounted a plate 49 and lever spring 47 which is under tension against a fixed post 48, electrically connected to ground through strap 59 and screw 60. As a battery usually has its negative terminal grounded, plate 49 may be referred to as

of positive polarity. The negative plate 52 and the lever spring 57 are mounted on the opposite side of 42. The outer end of spring 57 is under tension against a fixed post 58 electrically connected to strap 61 which serves as the terminal 5 to receive the primary lead wire. The negative plate 52, spring 57, post 58, and strap 61 are all insulated from the distributor. The two outer ends 51 and 50 of plate 49 serve to contact alternately against the spring contacts 53 and 54. The two outer ends 62 and 63 of plate 52 serve to contact alternately against the spring contacts 55 and 56. The spring contacts 53 and 55 are mounted in the frame 64, which is adjustable by means of screws 65, and the spring contacts 54 and 56 are mounted in the frame 66, which is adjustable by means of screws 67, each frame being adjusted and secured so that the plate contacts strike the spring contacts properly at each end of their stroke.

Frame 64 is electrically connected by strap 68 to the post 38a, so that frame 64 supplies current to the breaker arm contact 40. Frame 66 is electrically connected by strap 69 to the adjustable bracket 70 which carries the self-aligning contact 41, so that frame 66 thus supplies current to contact 41. It is obvious that when 62 contacts with 55, 50 contacts with 54, delivering positive current to the contact 41, while negative current goes to contact 40; when 51 contacts with 53, and 63 with 56, positive current goes to 40 while negative current goes to 41.

The operation of the transmuter mechanism may now be explained. As the distributor shaft revolves, the breaker arm bumper is pressed 35 against the lobes 30, while the transmuter bumper is pressed against the lobes 31. The location of the bumpers is such as to synchronize their movements. While the transmuter is in contact, the breaker arm opens; while the breaker arm remains open, the transmuter bar moves across to the opposite contacts; while on such contact, the breaker arm opens; while the breaker arm remains open, the transmuter bar moves back to the opposite contacts, thus completing the cycle. 45 The reference letters A and C in Fig. 4 correspond to the reference letters A and C of Fig. 1. The contacts B, B¹ correspond to the reference letter B, and the contacts D, D¹ correspond to the reference character D in Fig. 4. 50

As explained in Fig. 1, the wiring connections may be such that the current is reversed through the primary of the coil. This is highly advantageous as it allows the coil to operate similarly to an alternating current transformer. Such alternating or reversing of current tends to hasten the demagnetizing of the core after each impulse, so that the coil operates with efficiency at higher engine speeds than is possible with a constant polarity.

However, if preferred, my ignition system may be wired as in Fig. 2, without changing the direction of current through the coil, to avoid excess wiring to a remotely located coil.

Instead of using an oscillating transmuter, it 65 may be desirable or preferable, in certain constructions, to use instead a disk of Bakelite or other insulating material, with rings thereon, carbon contacts being mounted on a wiper arm and contacting the rings. Preferably, the disk 70 is mounted in the distributor base above the breaker arm mechanism, and the carbon contacts are mounted on the lower face of the wiper. Or, copper segments may be mounted on a small revolving drum, with carbon brushes engaging 75

the segments to receive the battery current and transmute it to reversed current.

The transmuting method prevents all pitting and burning of breaker contact surfaces. Inasmuch as one set of clean contacts with large bearing surfaces can transmit current fast enough for high speed engines, there is no need of supplying the conventional dual sets of breaker mechanisms. Therefore, with my transmuting mechanism, only one set of breaker points are required. As the transmuting mechanism costs no more than a breaker set, the complete distributor costs no more than the ordinary dual set distributor. Thus the transmuting method produces the above described advantages without any increase in manufacturing costs.

While I have described a specific ignition system, it is merely given by way of example to show one embodiment of the invention, and it is obvious that many changes in the general arrangement of the parts, in their specific form, in their size, and in their relative position, may be made without departing from the spirit and the scope of the invention as defined in the appended claims.

I claim:

1. In an ignition system the combination of an ignition coil, an interrupter, a source of current; a circuit including the primary of said coil, said interrupter and said source; switching means in said circuit operating each time said interrupter is open for alternately conditioning the circuit for reversal of current therethrough, whereby each closing of said interrupter will effect a reversal of said current, and a spark plug system fed by energy from the secondary of said coil.

2. In an ignition system the combination of an ignition coil, an interrupter, a source of current; a circuit including the primary of said coil, said interrupter and said source, a reversing switch in said circuit, means operating each time said interrupter is open for opening and reversing said switch, thereby reversing the direction in which current flows through said primary and said in-

terrupter each time the interrupter closes, and a spark plug system fed by energy induced in the secondary of said coil.

3. In a current reversing system, an ignition coil including a primary winding, an interrupter, a reversing switch, a source of direct current; connections between said winding, said interrupter, said switch and said source whereby the polarity relation of said source to said winding and said interrupter may be alternately reversed, 10 said switch and said interrupter operating in cycles each comprising a period during which said interrupter is open and said switch opens and reverses, and a period during which said switch remains in its reversed position and said 15 interrupter closes and opens, and a secondary winding and a circuit connected thereto to deliver oscillating current to a spark plug system.

4. In an ignition system, a coil including a primary winding, an interrupter connected in series 20 with said winding, a source of direct current, and switching means connected thereto for alternately reversing the polarity of the contacts of said interrupter, said switching means operating each time said interrupter contacts are 25 opened.

5. In an ignition system, an ignition coil including a primary winding; a circuit connected thereto including an interrupter, a reversing switch, and a source of current; an oscillatable 30 bar forming the moving element in said reversing switch, a cam for said interrupter, a second cam for controlling the movement of said bar, a shaft forming a common support for said cams, said cams being so timed relative to each other 35 that while said first cam is holding the interrupter open, said second cam shifts said bar to a reverse position, and while said first cam is closing and opening said interrupter said second cam is maintaining said bar in said reverse position, a secondary winding in said coil, and a spark plug system fed by energy from said secondary winding.

JAMES A. DORAN.
